(57) CLAIM

The ornamental design for a container for fragrant essence, as shown and described.

DESCRIPTION

FIG. 1 is a perspective view of the container for fragrant essence of the present invention.

FIG. 2 is a front side view of the container for fragrant essence of the present invention.

FIG. 3 is another perspective view taken at a different angle than in FIG. 1.

FIG. 4 is a top view.

FIG. 5 is a bottom view; and,

FIG. 6 is a rear side view of the container for fragrant essence of the present invention. Due to the symmetrical nature of the design, a right side view and a left side view of the container are identical to FIG. 6. In fact, due to the symmetrical nature of the design, all side views of the container are identical to those shown in FIGS. 2 and 6.

The patent or application file contains at least one drawing. Any indicia shown in broken lines in the drawings form no part of the design to be patented.
